UNITED STATES PATENT OFFICE.

THOMAS L. MARTIN, OF LEWISBURG, KENTUCKY.

EDUCATIONAL DEVICE.

SPECIFICATION forming part of Letters Patent No. 663,287, dated December 4, 1900.

Application filed November 18, 1899. Serial No. 737,542. (No model.)

To all whom it may concern:

Be it known that I, THOMAS L. MARTIN, residing at Lewisburg, in the county of Logan and State of Kentucky, have invented a new 5 and Improved Educational Device, of which the following is a specification.

This invention is an improved educational device and is adapted for use in teaching writing, spelling, arithmetic, the fundamental 10 principles of languages, or anything else that can be taught by copy.

The object of my invention is to provide a simple form of device which can be manipulated by a scholar under the direction of a 15 teacher and one in which the copy will be placed in front of the pen or pencil.

The construction and operation of the device or apparatus are as follows.

In the drawings, Figure 1 is a perspective 20 view of my improved device. Fig. 2 is a top plan view, and Fig. 3 is a section on the line 3 3 of Fig. 2.

In constructing the device I employ a stand or frame A, composed of the side pieces a, 25 connected by cross-rod a' and a², and said rod a² also acts as a hinge-rod for connecting the frame A with the forward section B, comprising the side pieces b and connecting-rods b' and b². The side pieces a are formed with 30 curved seats a³, in which rests a cylinder C, and passing through said cylinder is a shaft D, upon which is wound the ribbon E, upon which the copy is written.

The shaft D is operated by means of a crank 35 F, and carried upon said shaft outside the cylinder is a gear-wheel G, which meshes with another gear H, mounted upon the end of a shaft H', journaled in bracket h, projecting rearward from the side pieces a. The ribbon 40 passes out through an opening c in the front of cylinder and then forward and downward between the rods b' and b² and around the roller b⁴ on rod b³, then back under rod a² and cylinder over a roller K, and is wound upon 45 a spool H², mounted on shaft H'. The roller K is mounted on a shaft k, journaled in bracket k', extending from the sides a. By turning the crank F the shafts D and H' are revolved, and as the ribbon is wound upon 50 one it is unwound from the other, and the bars b' and b² and roller K act as tension devices to keep the copy taut. A small box or

receptacle L is mounted upon the cross-rod a' and in which pens, pencils, and sundries may be kept. Guide-disks M M are mounted 55 upon a shaft m, journaled between the sides b', and similar disks N N are mounted at the ends of the rollers K and H², the purpose of said disks being to keep the ribbon straight as it is wound from one roller to the other. 60

The slate, tablet, or sheet to be written upon is slid beneath the roller b⁴, mounted upon rod b³, and as the portion B is pivoted to the portion A said part B will move upward sufficiently to accommodate a thick or thin slate 65 or tablet. The roller b⁴ thus always rests and presses upon the slate-frame and assists in holding it fixed in place. The pupil may place the writing-point inside the roller b⁴, and it will thus be noted that the copy is directly in front of the writing point, while the roller b⁴ serves as a hand-rest. When one line is finished, the slate, tablet, or sheet can 70 be pushed under the roller b⁴ and another line written.

A device of this kind saves a teacher a great deal of time and trouble, as one teacher can direct one hundred pupils to turn to a certain line or page and copy the same, and it will only be necessary for the teacher to inspect the work. 75

While teaching writing various studies—such as spelling, arithmetic, and grammar—can also be taught, since a person constantly copying a number of words or examples in 85 arithmetic will be impressed with the manner of spelling and the rule for doing said examples.

Having thus fully described my invention, what I claim as new, and desire to secure by 90 Letters Patent, is—

1. An educational device comprising a main frame, ribbon-winding rollers which are geared together, a supplemental frame hinged to said main frame, so that it may be raised 95 as required, and having guide-rods arranged at its front end, one being higher than and in rear of the other, and a ribbon passing over said rolls and back to the winding-rollers, substantially as shown and described. 100

2. An educational device comprising the frame, a cylinder fixed therein and having a lengthwise slot in its front side, a rotatable crank-shaft passing axially through said cyl-

inder, a roller arranged parallel to said shaft, and meshing gears operatively connecting the cylinder and shaft, guide-rods arranged in the front portion of the frame, and a ribbon wound on the shaft and roller, and passing intermediately over said rods, as shown and described.

3. The educational device comprising the main frame adapted to rest upon a flat surface, the ribbon-winding shaft and roller arranged therein, and the supplemental or movable frame hinged to the main frame and having guide-rods, one of which is located at

its free end and slightly above the base or under side thereof, thus providing space in 15 which a copying device may be inserted and clamped, and a ribbon passing over such rod and attached to the winding devices, as shown and described.

In testimony whereof I have signed my 20 name to this specification in presence of two subscribing witnesses.

THOS. L. MARTIN.
